UNITED STATES PATENT OFFICE.

JAMES P. HOOPER, OF RUXTON, MARYLAND.

FABRIC BUFFING WHEEL.

Application filed March 24, 1925. Serial No. 17,874.

There are now on the market or otherwise obtainable through the regular commercial sources, various makes of fabric buffing wheels consisting each of a circular block or disk of cotton duck composed of numerous thicknesses of duck or similar fabric having a central aperture for the arbor. These wheels are well adapted for use in polishing metallic and similar articles having substantially regular surfaces whether they be flat or curved, but they are not adapted for use in place of a soft cloth to produce the final high polish that is desired in many instances or to clean and polish irregular surfaces as chased silverware or the like where the cleaning or polishing member must reach into the crevices and must not be so hard as to remove projecting portions, or where in other words a comparatively soft buffer is necessary.

The difficulty incident to providing a soft buffer for such purposes is to produce one which meets this requirement, and is at the same time of sufficient length of life to be more efficient in operation than a hand-wielded polishing cloth. The soft buffing wheels which have been made soon flare and flatten out until they become a shapeless mass of disintegrated fibre.

The object of the present invention is to produce a soft buffing wheel which will retain its shape and function as intended through a reasonable length of life.

In the preferred form the buffing wheel of the invention consists of a disk or circular block of fabric having a central aperture for the arbor and composed of alternate layers of soft cotton padding and of duck, the duck forming the outside surface on both sides of the wheel and being also placed between the respective layers of padding. The padding while it may be of any suitable type is, in the form of the invention shown and preferably of the variety shown in my United States Patent No. 1,471,029, dated Oct. 16, 1923. This type of padding has a weft or filling of soft cotton resembling a cotton roving and a warp of thread or yarn which is interwoven between and about the filling, holding the soft cotton weft in posi-

tion without unduly compressing the soft cotton or reducing its elasticity and cushioning properties.

In building up the buffer wheel the respective thicknesses of cotton padding are laid with the cotton roving or weft in each instance at right angles to the corresponding wefts or rovings of the adjacent layers of similar material, the manner of laying the duck between the thicknesses of cotton padding being less important, though this may to advantage be likewise laid with the warp and filling of each layer of duck at right angles to the warp and filling of the adjacent layers of the duck.

When the fabric is thus laid in the construction of each wheel, it is preferably stitched through and through with a series of spaced circular seams concentric with the wheel and with the central opening therein for the arbor, and also with a series of radial seams which may be either arranged with a loop or U-shaped curve spaced slightly outwardly from the centre or in the form of a V with the vertices near the centre so as to give sufficient room for the stitching.

In the preferred form the U-shaped or looped seams are combined with the V-type radial seam.

Within the scope of my invention I also provide the buffing wheels when desired with an abrasive element which may be composed of a finely powdered abrasive as tripoli, corundum, rouge or pumice applied to the fabric in the form of a paste before assembling the wheel. This may be applied to all of the materials or to the soft padding only, or to alternate layers of the soft padding, and the paste may be formed by mixing with the finely powdered abrasive either water, adhesive, a drying oil or a non-drying oil, depending upon the character of the work to be done and the nature of the articles to be buffed. The paste may be made thin and the fabric which is so treated may be saturated with it, or the abrasive may be otherwise applied to the fabric within the scope of my invention.

In the accompanying drawing I have illustrated a preferred and secondary form of

buffer wheel constructed in accordance with my invention.

In the drawings—

Figure 1 is a side elevation of the preferred form of wheel.

Figure 2 is a plan of the same.

Figure 3 is a fragmentary section on the line 3, 3 of Figure 1 and on a somewhat enlarged scale.

Figure 4 is a fragmentary perspective of the wheel showing the different layers of fabric and padding broken away to disclose the underlying portions.

Figure 5 is a side elevation of a slightly modified form of wheel in accordance with the invention.

Referring to the drawings by numerals, each of which is used to indicate the same or similar parts in the different figures, the 20 buffering wheel 1, as shown in Figures 1, 2, 3 and 4, consists of four layers or thicknesses of soft cotton or similar padding 2, 3, 4, 5. This padding, as shown, consists of parallel lines or strands 6 of soft cotton and a 25 knitted thread mesh 7 consisting of loops or other arrangement of the threads extending transversely to the soft strands and holding the soft strands in position. This is the preferred arrangement, though the minute 30 details described are not regarded as essential to the invention. The alternate adjacent layers or thicknesses of cotton padding 2, 3, 4, 5, are preferably arranged with the soft strands 6 resembling roving which 35 though described as of cotton, may be of any suitable fibre, at right angles to each other, that is the soft strands 6 of the layers or thicknesses of cotton padding 2 and 4 are at right angles or at an angle approaching a 40 right angle to the soft strands 6 of the layers of padding 3 and 5.

While the cotton padding arranged as described presents a considerable resistance to wear, it is preferably sustained by alternate 45 layers of duck 8, 9, 10, 11, 12, or other material, sufficiently soft and having sufficient supporting and wear-resisting properties for this purpose. The alternate layers of duck 8, 10, 12 may to advantage be placed with 50 their warp and weft at right angles to the respective warp and weft threads of the alternate intermediate layers 9 and 11.

Each of the buffering members 1 is preferably of a disk form with a central aperture 55 14 for the arbor.

The respective layers of material may be secured together in any suitable manner. Preferably and as shown, the thicknesses or 60 layers of fabric are sewed together by circular seams 15 sewed through and through the registering overlying layers of padding and duck or other fabric and concentric with the arbor hole 14; and in addition to the concentric seams 15, in the form shown in Figures 1, 2, 3, and 4, I have also shown radial

seams 16, and placed intermediately of the radial seams 16 I have shown alternately-placed U-pattern seams 17 having their legs 18 substantially radial and the bend of the U 19 tangent to one of the inner circles 15, though 70 this exact arrangement is not essential, and in addition to the main U-shaped seams 17, I have shown lesser intermediate U-pattern seams 20 having their legs radial and the bend of the U tangent to one of the intermediate circular seams 15.

In Figure 5, I have shown a slightly different form of buffer wheel having the through and through seams differently arranged. This buffer wheel has circular concentric seams 15, the circular seams in both instances being preferably continuous for convenience in sewing, and radial V-seams 21 extending outwardly from one of the circular seams 15 near the centre but spaced 85 slightly outwardly to prevent undue thickening and rigidity of the central portion. I have also shown in this connection four radial seams 16.

While soft buffer wheels have been found 90 desirable for various purposes, it has been exceedingly difficult and almost impossible to produce a soft wheel which has any considerable length of life sufficient to make this type of wheel commercially acceptable. The 95 structure disclosed is found to serve the purpose to great advantage, as the arrangement of the layers of cotton padding between the layers of duck with the circular seams and the radial seams provides a soft wheel which 100 will perform the finest buffering operation and give the highest polish and at the same time has a considerable length of life.

The abrasive material referred to in the preamble is not shown in the drawing, as it 105 does not necessarily change the appearance of the fabric as illustrated.

The arrangement of the particular type of padding described with the soft cotton strands 6 in the alternate layers at right angles to each other, is of great advantage as the fabric as shown with the thread loops 7 tends to retain its shape and the arrangement of the soft strands at right angles, so that the ends of substantially half of these soft 110 strands or an average of half of them are presented at the operative edge of the wheel at all points is of great advantage in that it gives a uniform polishing effect and prevents disintegration, and with the protection incident to the arrangement of the alternate layers of duck with the through and through sewing, gives a wheel the length of life which compares favorably even with the solid duck wheels and which is much 115 more effective where a soft buffering effect is desired.

I have thus described specifically and in detail two slightly different forms of my invention in order that the nature and opera- 120

tion of the device may be fully understood; however, the specific terms herein are used descriptively rather than in a limiting sense, the scope of the invention being defined in the claims.

What I claim and desire to secure by Letters Patent is:

1. A buffer wheel composed of layers of padding, the padding having parallel soft strands extending in one direction and transverse threads holding the soft strands in position, the soft strands of the alternate layers of padding being placed transversely to each other, alternate layers of a flexible material having greater wear-resisting properties than the padding serving to protect the

padding and prevent disintegration of the wheel, and means for securing the respective layers together.

2. A buffer wheel composed of layers of padding, the padding consisting of parallel soft strands and transverse threads holding the soft strands in position, alternate layers of a flexible material having greater wear resisting properties than the padding serving to protect the padding and prevent disintegration of the wheel, and means for securing the respective layers together. 25

Signed by me at Baltimore, Maryland, this 23d day of March, 1925.

JAMES P. HOOPER.
